UNITED STATES PATENT OFFICE.

ELNA M. DE NEERGAARD, OF NEW YORK, N. Y.

DESIGN FOR A LOOM-FRAME.

52,910.

Specification for Design.

Patented Jan. 28, 1919.

Application filed April 24, 1918. Serial No. 230,598. Term of patent 3½ years.

To all whom it may concern:

Be it known that I, ELNA M. DE NEERGAARD, a subject of the King of Denmark, residing at New York, in the county of New York and State of New York, have invented a new, original, and ornamental Design for Loom-Frames, of which the following is a specification, reference being had to the accompanying drawing, forming part thereof.

In the drawing the figure is a perspective view of the loom frame.

I claim:—

The ornamental design for a loom frame, as shown.

ELNA M. DE NEERGAARD.

Witnesses:

HUGH H. OTT,
ANN V. DOYLE.
